UNITED STATES PATENT OFFICE.

ROBERT A. LEET, OF OAKLAND, CALIFORNIA.

POISON-BOTTLE CORK.

985,354.

Specification of Letters Patent. Patented Feb. 28, 1911.

Application filed April 12, 1910. Serial No. 554,973.

To all whom it may concern:

Be it known that I, ROBERT A. LEET, a citizen of the United States, residing at Oakland, in the county of Alameda and State of California, have invented certain new and useful Improvements in Poison-Bottle Corks, of which the following is a specification.

This invention relates to means for preventing the inadvertent use of poison, and the principal object of the same is to provide simple means for attachment to a cork or stopper of a poison bottle or other receptacle which is provided with means that will serve to remind the user that the receptacle contains poison.

In carrying out the objects of the invention generally stated above it will be understood, of course, that the essential features thereof are necessarily susceptible of changes in details and structural arrangements, one preferred and practical embodiment of which is shown in the accompanying drawings, wherein:—

25 Figure 1 is a perspective view of a stopper equipped with the improved indicating attachment. Fig. 2 is a top plan view thereof. Fig. 3 is a vertical sectional view taken on the line 3—3, Fig. 2.

30 Referring to said accompanying drawings by numerals, it will be seen that the improved indicator comprises a cap that is preferably formed of sheet metal the top 1 of which has slotted portions the material of which is bent inward to provide the attaching prongs 2. Said top is provided with the annular pendent flange 3 the free edge of which flares outward as indicated

at 4 to facilitate the placing of a stopper 5 therein so that the prongs 2 will enter said stopper as clearly shown in Fig. 3. The material of which flange 3 is formed is provided with regularly spaced crimped portions which form flat laterally arranged outstanding projections 6 which preferably taper to provide the blunt point 7.

40 The cap is preferably formed of resilient sheet metal so that the flange 3 will tightly embrace the stopper 5, and assist prong 2 in retaining the stopper and cap in rigid but separable relation.

45 As will be clear, the arrangement of the projections 6 is such that they will attract the attention of the user to the bottle, and as an additional safeguard, the top of the 55 cap is provided with the word "Poison" which is displayed in a conspicuous position so that when projections 6 have attracted the attention of the user, the said word will be a further reminder of the dangerous 60 character of the contents of the bottle.

55 What I claim as my invention is:—

A poison indicator comprising a cap for a bottle stopper formed of a single sheet of material and provided with a stopper engaging flange, said flange being outwardly flared at its outer end and being intermediate crimped to provide regularly spaced outstanding flat projections having curved edges tapering to a blunt point.

65 70 In testimony whereof I affix my signature in presence of two witnesses.

ROBERT A. LEET.
